WHEEL COVER

George Albert Lyon, 13831 W. Chicago Blvd.,
Detroit 28, Mich.

Filed July 19, 1957, Ser. No. 672,891

7 Claims. (Cl. 301—37)

This invention relates generally to wheel structures and to methods of making same, and still more particularly to a cover and handle grip structure and method of attaching the handle grips or spoke simulating elements to the cover.

In the past there has been considerable demand for cover structures having radially extending spoke simulating elements or handles. In the past most of the cover structures having this type of construction have been highly involved ordinarily requiring a multi-part cover structure which on occasion has involved the use of three or more circular cover members. It will be appreciated that this type of cover construction is highly involved involving close tolerances between the parts and in addition is considerably more expensive to manufacture.

The present cover structure is believed to be considerably more advantageous than prior cover constructions of this general type since the components of the cover may be more simply manufactured at a substantially reduced cost, and since the components of the cover may be assembled together much more readily.

Accordingly, an object of this invention is to provide a new and improved cover structure having ornamental and utilitarian handle grips or spoke simulating elements.

Still another object of this invention is to provide a novel method of attaching handle grips to a wheel cover.

Yet another object of the present invention is to provide handle grips or spoke simulating elements which elements are engaged under resilient tension with the cover and which may be readily assembled with and removed from the same.

According to the general features of the present invention there is provided in a wheel structure, a wheel including rim and body parts, a wheel cover structure for overlying disposition upon the wheel including a series of circumferentially spaced openings defined by edges, means cooperable with the structure for maintaining the same upon the wheel, handles cooperable with the edge of the openings for facilitating assembly and removal of the structure with respect to the wheel, the handles each having a pivot, a cam, and a shoulder with the pivot being engaged against the edge and upon pressure being applied to the handle the cam also cooperating with the edge until the shoulder snaps over the edge and engages the cover thereby maintaining the handle under resilient tension with the cover.

According to still other features of the present invention there is provided in a method of attaching gripping handles to a vehicle wheel cover, the steps of fulcruming an end area of the gripping handle upon a limited area of the cover, applying pressure to the opposite end of the handle causing another area of the handle to be cammed against another cover area, and setting up counter forces between the handle and the cover upon the opposite end of the handle being moved to a predetermined point whereby the tension between the gripping

2

handle and the cover is retained despite the pressure against the opposite end of the handle being released.

Other objects and features of the present invention will more fully become apparent in view of the following detailed description taken in connection with the accompanying single sheet of drawings illustrating therein a single embodiment and in which:

Figure 1 is a side elevation of the wheel structure;

Figure 2 is an enlarged fragmentary cross sectional view taken substantially on the line II—II of Figure 1 looking in the direction indicated by the arrows;

Figure 3 is an enlarged fragmentary cross sectional view taken on the line III—III of Figure 1 looking in the direction indicated by the arrows; and

Figure 4 is an enlarged fragmentary cross sectional view in full and dotted lines showing the handles in preliminary and intermediate positions with respect to the cover.

As shown on the drawings:

The reference numeral 10 indicates generally the wheel structure which wheel structure has a conventional wheel comprised of a body part 11 and a multi-flanged tire rim 12. The tire rim 12 supports a conventional tire structure 13 which may be either of the tube or tubeless type and which is adapted to be inflated by inserting air in the valve stem 14 shown in Figure 1. The body part and tire rim are suitably joined together at 15 by means of welding and the like. The body part 11 is provided with a bolt-on flange 16 which flange has a series of apertures 17. The apertures 17 are adapted to be aligned with lugs positioned on the axle of a vehicle and then guided in assembly therewith with nuts (not shown) threaded onto the lugs to clamp the body part 11 to the axle.

The tire rim 12 includes a generally radially and axially outwardly extending annular intermediate rim flange 18 and a generally radially outwardly extending annular rim flange 19.

Cooperable with the above defined wheel is a novel cover structure 20 for overlying the wheel which cover structure includes a circular cover member 21 and a series of circumferentially spaced spoke-simulating elements or handle grips 22. It will be noted the handle grips are totally independent of one another except that they are all attached to the side wall area 25.

The circular cover member 21 includes a central crown area 23 which is bounded at its outer periphery by an annular dished portion 24 defined by opposed side wall areas 25 and 26. Disposed at the outer periphery or boundary of the dished portion 24 is an annular margin 27.

The cover structure 20 may be provided with any suitable means for maintaining the cover structure in assembly with the vehicle wheel. Preferably, the cover is provided with some kind of snap-on, pry-off type of retaining means. In the illustrated instance the cover margin 27 is turned under and formed into an annular resiliently deflectable cover flange structure 28 for self retaining cooperation with the intermediate rim flange 18.

The flange structure 28 includes a radial flange 29 spaced axially inwardly of the cover margin 27 and which is adapted to be bottomed against the rim 12 at the junction of the flanges 18 and 19 to provide a rigid back-up. The flange 29 is connected to a generally radially and axially inwardly extending flange 30. The annular flange 30 is provided at circumferentially spaced intervals with generally wedge shaped axially inwardly extending flanges which are return bent providing generally radially and axially outwardly extending terminals 31 which terminals have edges 32 for edgewise biting engagement with the terminal rim flange 19.

The dished cover portion and more particularly the side wall area 25 is provided with circumferentially spaced annular edge areas or edges or seats or seat surfaces 33 which are suitably cut out of this side wall area and which edges or seats define openings, as illustrated, for the receipt of the spoke simulating elements 22.

The spoke simulating elements 22 as illustrated are each generally U-shaped in cross section.

Each of the grips or arms 22 is generally U-shaped along its length. The arms 22 include divergent sides 34-34 which are connected together at one end by a base portion 35. As will be noted in Figure 3, the sides 34-34 diverge generally axially inwardly with respect to the base portion 35.

The arms 22 are provided with a radially inner terminal portion 36. The terminal portion, and more particularly, the sides 34 are provided with a pivot comprising notched edges 37-37 which notched edges are adapted to interlockingly cooperate with the edge of the opening 33. As is shown in Figure 4, the notched edge 37 is fulcrummed upon the edge of the opening 33.

The terminal portion, and more particularly the base portion 35 of the terminal portion is provided with a radially inwardly axially outwardly flared cam surface 38 terminating in a shoulder 39. As will be appreciated from Figure 4, the cam surface 38 is engageable against the edge of the opening as the notched edges 37 are fulcrummed on the edge of the opening upon the application of an axially inward force against the outer terminal of the arm or handle grip 22. Upon the exertion of a predetermined force, the cam surface is moved completely radially outwardly of the opening 33 and the shoulder 39 is engaged against the radially outer side of the side wall area 25 at the periphery of the opening 33. It will be appreciated that as the arm is fulcrummed upon the edge of the opening the cam surface 38 is caused to resiliently deflect until the shoulder 39 is permitted to snap free of the edge defining the opening 33 whereupon it bears against the radially outer side of the side wall area 25.

It will be further appreciated from Figure 3 that as the divergent sides are caused to be moved through the openings 33 in a radially outward direction the sides are deflected towards one another slightly so that when the notched edges 37-37 are engaged against the edge of the opening 33, the notched edges are placed under a slight degree of resilient tension. This relationship allows a closer cooperation between the arms 22 and the side wall area 25 and also aids in preventing the notched edges 37 from becoming disengaged from the edge of the opening 33 during the rotation of the wheel structure.

As is also most clearly shown in Figure 3, the arm 22 is provided with laterally turned ears 40-40 which constitute integral extensions of the sides 34-34. These ears serve a multiple purpose in that they not only aid in preventing the notched edges 37 from becoming disengaged from the edge of the opening, but in addition, should the notched edges 37 become disengaged from the edge of the opening or should the shoulder 39 become disengaged from the side wall area 25 at the periphery of the opening 33, the arm or handle grip 22 will not be lost during further rotation of the wheel since these turned ears make it practically impossible for the arm 22 to pass radially outwardly through the opening 33 in its entirety. Thus, if one of the arms 22 becomes disengaged with respect to the edge of the opening, the arm will not be lost and may be restored to its original position. Thus if the laterally offset ears 40 are utilized, the arms 22 must be urged radially outwardly through the openings 33 in order for the arms to be assembled with the cover 21.

To assemble the cover with respect to the wheel, after the arms 22 have all been assembled with the side wall area 25, the cover opening 41 is aligned with respect to the valve stem 14 by using the handles 22 to hold the cover opening 41 in axial alignment with the valve stem 75

14. Thereafter, the cover is urged axially inwardly by applying a force to the cover through the handles 22 until the edges 32 engage under resilient tension with respect to the intermediate rim flange 18 to secure the cover structure 20 in assembly with the tire rim 12. Removal of the cover structure 20 may be brought about by inserting a pry-off tool underneath the outer margin 27 of the cover and upon twisting of the pry-off tool the tension between the edges 32 and the intermediate rim flange 18 may be relaxed and an axially outward force may be applied through the handles 22 to pull the cover off of the wheel.

Should it be desired to remove one or more of the handle elements 22 a force may be applied to the radially outer end of the handles 22 in the direction indicated by the arrow 42 until the shoulder 39 is caused to be disengaged from the side wall area 25 at the periphery of the opening 33. At this point, the notched edges 37 may be disengaged from the edge of the opening 33 and the arm 22 may be pushed radially inwardly through the opening 33 and removed from the cover 21.

It will be understood that modifications and variations may be effected without departing from the scope of the novel concepts of the present invention.

I claim as my invention:

1. In a wheel structure, a wheel including rim and body parts, a cover structure overlying the wheel and means between the wheel and the cover structure for retaining the cover structure in assembly with the wheel, said cover structure including a wheel cover member and means for assisting in the assembly and removal of the wheel cover member upon the wheel which means comprises spaced handle elements, retaining means between each of said handle elements and said wheel cover member with each of said handle elements in snap-on, pull off assembly with the cover member and with each of said handle elements being totally independent of one another in the assembly and removal of the elements from the wheel, said cover member having spaced openings defined by edges with each of said edges cooperable with one of said handle elements, said handle elements each having a U-shaped terminal portion with sides of the terminal having notched edges fulcrummed on the edge of the opening, said U-shaped terminal portion having a base portion between the sides provided with a cam surface and a shoulder with said cam surface cammingly engageable against the edge of the opening until the shoulder snaps over the edge and engages the cover member to maintain the terminal portion of the handle element in assembly with the cover under resilient tension, said sides of said U-shaped terminal portion provided with laterally turned ears disposed on opposite sides of said shoulder for engagement against the inner side of the cover to insure that the notched edges do not disengage from the edge of the opening during the rotation of the wheel structure.

2. In a wheel structure, a wheel including rim and body parts, a wheel cover structure for overlying disposition upon the wheel including a series of circumferentially spaced generally radially outwardly facing openings defined by edges, means cooperable with said structure for maintaining the same upon the wheel, circumferentially spaced generally radially outwardly extending handles cooperable with the edge of said openings for facilitating assembly and removal of the structure with respect to the wheel, said handles each having a pivot, a cam, and a shoulder with said pivot being engaged against the edge and upon pressure being applied to the handle the cam also cooperating with the edge until the shoulder snaps over the edge and engages the cover thereby maintaining the handle under resilient tension with the cover.

3. In a vehicle wheel cover structure, a wheel cover member having means for maintaining the wheel cover member upon a vehicle wheel, pivot means and abutment means on said cover member, and said cover member having a second means for assisting in the assembly and

removal of the cover structure from the vehicle wheel comprising circumferentially spaced generally radially outwardly extending handle members, each of said handle members having retaining means generally at its radially inner end including a pivotal area fulcrummed on said pivot means, said retaining means also including a cam surface and a shoulder operable upon pivoting the handle member upon the pivot means causing the cam surface to be engaged against abutment means with the shoulder movable with the cam surface until the shoulder snaps behind the abutment means.

4. In a wheel structure, a wheel including rim and body parts, a cover structure overlying the wheel and means between the wheel and the cover structure for retaining the cover structure in assembly with the wheel, said cover structure including a wheel cover member and means for assisting in the assembly and removal of the wheel cover member upon the wheel which means comprises spaced handle elements, retaining means between each of said handle elements and said wheel cover member with each of said handle elements in snap-on, pull-off assembly with the cover member and with each of said handle elements being totally independent of one another in the assembly and removal of the elements from the wheel, said cover member having spaced openings defined by edges with each of said edges cooperable with one of said handle elements, said handle elements each having a U-shaped terminal portion with sides of the terminal having notched edges fulcrummed on the edge of the opening, said U-shaped terminal portion having a base portion between the sides provided with a cam surface and a shoulder with said cam surface cammingly engageable against the edge of the opening until the shoulder snaps over the edge and engages the cover member to maintain the terminal portion of the handle element in assembly with the cover under resilient tension.

5. In a wheel structure, a wheel including rim and body parts, a cover structure overlying the wheel and means between the wheel and the cover structure for retaining the cover structure in assembly with the wheel, said cover structure including a wheel cover member and means for assisting in the assembly and removal of the wheel cover member upon the wheel which means comprises spaced handle elements, retaining means between each of said handle elements and said wheel cover member with each of said handle elements in snap-on, pull-off assembly with the cover member and with each of said handle elements being totally independent of one another in the assembly and removal of the elements from the wheel, said cover member having spaced openings defined by edges with each of said edges cooperable with one of said handle elements, said handle elements each having a U-shaped terminal portion with sides of the terminal having notched edges fulcrummed on the edge of the opening, said U-shaped terminal portion having a base portion between the sides provided with a cam surface and a shoulder with said cam surface cammingly engageable against the edge of the opening until the shoulder snaps over the edge and engages the cover member to maintain the terminal portion of the handle element in assembly with the cover under resilient tension, said sides extending divergently relative to said base portion and having deflectable areas engageable under tension with the edge of the opening when the notched edges are engaged with the edge of the opening.

6. A cover structure for overlying a wheel with means thereon disposable between the wheel and the cover structure for retaining the cover structure in assembly with the wheel, said cover structure including a wheel cover member and means for assisting in the assembly and removal of the wheel cover member upon the wheel which means comprises spaced handle elements, retaining means between each of said handle elements and said wheel cover member with each of said handle elements in snap-on, pull-off assembly with the cover member and with each of said handle elements being totally independent of one another in the assembly and removal of the elements from the wheel, said cover member having spaced openings defined by edges with each of said edges cooperable with one of said handle elements, said handle elements each having a U-shaped terminal portion with sides of the terminal having notched edges fulcrummed on the edge with which it cooperates, said U-shaped terminal portion having a base portion between the sides provided with a cam surface and a shoulder with said cam surface cammingly engageable against the edge of the opening until the shoulder snaps over the edge and engages the cover member to maintain the terminal portion of the handle element in assembly with the cover under resilient tension.

7. A cover structure for overlying a wheel with means thereon disposable between the wheel and the cover structure for retaining the cover structure in assembly with the wheel, said cover structure including a wheel cover member and means for assisting in the assembly and removal of the wheel cover member upon the wheel which means comprises spaced handle elements, retaining means between each of said handle elements and said wheel cover member with each of said handle elements in snap-on, pull-off assembly with the cover member and with each of said handle elements being totally independent of one another in the assembly and removal of the elements from the wheel, said cover member having spaced openings defined by edges with each of said edges cooperable with one of said handle elements, said handle elements each having a U-shaped terminal portion with sides of the terminal having notched edges fulcrummed on the edge with which it cooperates, said U-shaped terminal portion having a base portion between the sides provided with a cam surface and a shoulder with said cam surface cammingly engageable against the edge of the opening until the shoulder snaps over the edge and engages the cover member to maintain the terminal portion of the handle element in assembly with the cover under resilient tension, said sides extending divergently relative to said base portion and having deflectable areas engageable under tension with the edge of the opening when the notched edges are engaged with the edge of the opening.
